AUTOMATIC FOCUS CONTROL FOR
CATHODE-RAY TUBES

Arthur H. Mankin, North Merrick, N. Y., assignor
to Philco Corporation, Philadelphia, Pa., a corporation of Pennsylvania

Application April 29, 1947; Serial No. 744,586

13 Claims. (Cl. 315—31)

1.

The invention herein described and claimed relates to cathode-ray tubes, and in particular to means for achieving and maintaining optimum focus of the electron beam.

The invention is employable in cathode-ray systems, particularly radar and television systems, to obtain patterns or images of improved resolution and excellent detail. In radar systems, it is important that the indication on the screen be sharp and in good detail. And in television systems, fine grain pictures of good resolution are highly desirable.

In accordance with the invention, means are provided for developing control or correcting signals indicative of the departure of the cathode-ray beam from sharp focus, and in accordance with a preferred embodiment, these control signals are employed to so adjust automatically the focusing currents or potentials that optimum focus is attained.

It is an object of this invention to provide means responsive to variations in the cross-sectional area of the electron beam at the screen of a cathode-ray tube.

It is another object of this invention to derive voltages from means adapted to be responsive to focal variations in the beam of a cathode-ray tube and to utilize said voltages degeneratively to correct unwanted departures of the beam from sharp focus.

It is another object of this invention to provide automatic means for obtaining optimum focus of the electron beam of a cathode-ray tube.

Another object of this invention is to provide means capable of operating in a conventional television receiver to adjust automatically the beam focus for sharp image resolution and good detail.

These and other objects, advantages and features of the invention will become clear from the following detailed description and from the accompanying drawings wherein:

Figure 1 is a representation, partly schematic, partly diagrammatic, of a circuit embodying a preferred form of the invention; and

Figure 2 is a graphical representation which will be helpful in understanding the invention.

Referring now to Figure 1, there is shown, in the lower center of the figure, an oscillator 10 whose output voltage is applied across a parallel combination, one branch of which comprises primary winding P of transformer 11, and the other branch of which comprises series combined resistors 12 and 13. Resistors 12 and 13 form a voltage divider by means of which a portion of

the output voltage of oscillator 10 is impressed upon the cathode of tube 14.

Resistor 12, which will ordinarily be considerably smaller in magnitude than resistor 13, also functions as the biasing resistor for the tube, bias being provided by means of cathode resistor 12 and bleeder resistor 48 connected as a voltage divider across a source of voltage, B+. The values of resistors 12 and 48 are so chosen that the bias is as desired and relatively independent of plate-current variations.

The anode of tube 14 is connected to a source of positive potential, B+, by way of conductor 15 and the auxiliary focusing coil 16 of cathode-ray tube 17. The function of the auxiliary focusing coil will become clear as the description proceeds. The main focusing coil 18 is connected from the source of positive potential, B+, to ground by way of variable resistor 19 employed as a manual focus control.

Cathode-ray tube 17 is conventional in most respects, and in addition to focusing coils 16 and 18, the tube includes the usual filament 21, cathode 22, control grid 23, fluorescent screen 24, and, though not shown, conventional horizontal and vertical deflection means. The dotted-line 25 depicts the electron beam. And though cathode-ray tube 17 is shown in Figure 1 to be a magnetically focused tube, it is to be understood that the present invention is applicable equally to cathode-ray tubes having electrostatic focusing means.

In accordance with the present invention, there is fastened to the face of tube 17 a pickup element 20. Pickup element 20 may take a number of different forms. It may comprise a conductive metallic plate, or it may be a mesh-like metallic screen. It may cover a small portion of the face of the tube, or it may cover the entire face. In the latter event, element 20 will ordinarily have to be transparent and may comprise, for example, a very thin coating of gold, silver, or aluminum applied, as by evaporation methods, to the inner or outer surface of the face of the tube.

Pickup element 20 is electrically connected to the input circuit of tuned amplifier 26. The output circuit of amplifier 26 includes a load resistor 27 connected between the mid-point of secondary winding S of transformer 11 and ground. Opposite ends of secondary winding S are connected as shown to the cathode of diode 28 and to the anode of diode 29. The plate circuit of diode 28 includes an R. C. network 30 comprising parallel combined capacitor 31 and resistor 32. The cath-

ode circuit of diode 29 includes R. C. network 34 comprising parallel-combined capacitor 35 and resistor 36.

The circuit elements comprising transformer 11 and diodes 28-29, together with the associated load impedances, form a known type of phase-comparator circuit.

The output circuits of diodes 28 and 29 are connected to a voltage-combining network 38 comprised of resistors 39 and 40. These resistors are of large and equal magnitudes. The common junction of resistors 39-40 is connected to the grid of tube 14.

The arrangement thus far described comprises a preferred form of the basic automatic-focus-control circuit. An understanding of the practical advantages of the new circuit may, however, be best obtained by describing the operation of the circuit when employed in a television receiver, and toward that end there is included in Figure 1 several components of a conventional television receiver, together with one or two components not ordinarily included in such a receiver but desirable for best operation of the focus control system of the present invention. The circuits of all of these components are known in the television and/or radar arts and the components are therefore merely shown in block form in Figure 1 identified by appropriate descriptive markings and by reference numerals 41-47 inclusive.

Referring now to Figure 2, there is shown a graphical representation of the manner in which the potential, of that portion of screen 24 which is under electron bombardment, varies in accordance with changes in the strength of the total focusing current through focusing coils 16 and 18, assuming that other factors, such as beam intensity, beam deflection speed, and incident angle of bombardment are fixed. The variations in screen potential occurring in the immediate vicinity of element 20 are picked up by the capacitive, or other, coupling action of element 20 and these potential variations are therefore referred to in Figure 2, and hereinafter in the specification, as pickup voltages.

The graph of Figure 2 shows that, as the total focusing current is increased from a low to a high value, the pickup voltage will decrease from a high value to a minimum value and then increase again to a high value. In Figure 2, the curve is substantially symmetrical on both sides of the point of minimum pickup voltage but it is to be understood that the curve may not be, and need not be, symmetrical in all cases. It has been observed that when the cross-sectional area of the spot is minimum, i. e., when the beam is focused most sharply upon the fluorescent screen, the pickup voltage is minimum, assuming the other factors mentioned above to have remained fixed. And when the beam is less sharply focused, the pickup voltages are higher. The observed manner in which the potential of the bombarded area of screen, i. e., the pickup voltage, varies with variations in beam focus may be explained as follows: At sharpest focus, i. e. when the area of the beam spot is a minimum, the ratio of the number of secondary electrons knocked out of the screen by each bombarding electron is a minimum. Although minimum, the ratio is ordinarily greater than one, and since more electrons have been lost than gained, the potential of the bombarded area is positive with respect to its potential prior to bombardment. As the beam spot increases in size, the ratio of

secondary electrons emitted to primary electrons arriving increases, and the bombarded area of screen becomes still more positive.

It will be understood that the extent of the departure of the beam from sharpest focus is a function of the extent of the deviation of the focusing current from optimum value. In Figure 2, the optimum focusing current is indicated as being five units, the value of the unit being purely arbitrary. If the focusing current be less than optimum, the focal point of the beam becomes located in front of the screen, i. e. on the viewing side of the screen, while if the focusing current be greater than optimum, the focal point becomes located in back of, i. e. on the gun side of, the screen.

It will be observed in Figure 2 that, for values of focusing current which differ by an equal amount from the optimum value, substantially equal voltages are derived from pickup element 20. For example, the voltage derived when the focusing current is equal to one unit is substantially equal to that derived when the focusing current is nine units. Consequently, while the voltages derived from pickup element 20 may be indicative, under the proper conditions, of the extent to which the focusing current has deviated from optimum value, the derived voltages, per se, are not indicative of the direction in which the deviation has occurred.

The present invention provides means responsive to the direction, as well as to the magnitude, of the focal deviation. The invention contemplates modulating the focusing current in such manner as to vary the beam focus, preferably at a relatively rapid rate, the extent of the focal excursions being so small as not to be discernible to the eye of the observer, but capable of measurement, nevertheless, by electronic means. The phase of the alternating component of the voltage picked up by element 20 is then compared with the phase of the modulating signal, and in this manner a determination may be made as to whether the beam is under-focused, over-focused, or correctly focused.

The above general remarks regarding phase comparison will become clear by considering Figure 2 wherein sine wave I_1 represents the A.-C. component of a current sent through auxiliary focusing coil 16 (Figure 1) at a time when the total focusing current is one unit (Fig. 2), i. e. when the D.-C. current through main focusing coil 18 plus the D.-C. component of the current through auxiliary coil 16, is one unit. The beam is then under-focused. As the alternating current I_1 flows through coil 16, and the total focusing current swings back and forth about the mean value of one unit, a pickup voltage V_1 is derived which is substantially 180° out of phase with the current I_1 .

In Figure 2, sine wave I_2 represents an alternating current, similar to I_1 , sent through auxiliary focusing coil 16 at a time when the beam is over-focused, as for example, when the total mean focusing current is seven units. In this case, a pickup voltage V_2 is derived from element 20 which is in phase with sine wave current I_2 . Observe that the phase of the pickup voltage changes 180° when the focus of the beam moves from one side of optimum focus to the other.

The operation of the circuit of Figure 1 will now be described in detail. To facilitate the first portion of the detailed description it will be assumed that electron beam 25 is of fixed intensity and is being rapidly deflected back and forth

across the screen in the vicinity of pickup element 20. The effect upon the operation of the focus-control circuit of intensity modulating the beam will be discussed later.

For purposes of describing clearly the operation of the circuit, assume the condition that a total average focusing current of one unit (Figure 2) flows through main and auxiliary focusing coils 18 and 16. Beam 25 is therefore out of focus. Observe that a small portion of voltage W from sine wave oscillator 10 is impressed across cathode load resistor 12 of triode 14 and appears in amplified form in the plate circuit of the tube. The gain of tube 14 need not be high and the A.-C. component of sine wave current I_1 which flows through the auxiliary focusing coil 16 is desirably small, being of such magnitude that, although beam 25 is thereby modulated in focus, the focal excursions are too small for the eye to perceive. The excursions are large enough, however, to effect variations in screen potential of such magnitude that pickup element 20 is responsive thereto.

The variations in screen potential are, by means of element 20, capacitively coupled to the input circuit of tuned amplifier 26, tuned to the frequency of the sine wave oscillator 10. In a television system, the frequency of sine wave oscillator 10 may desirably be of the order of ten to twenty times line frequency. In the usual television system, line frequency is approximately 15 kc., and the frequency of sine wave oscillator 10 may be of the order of 150 to 300 kc. Either substantially lower, or substantially higher, frequencies may, however, be employed. In some cases, it may be advantageous to have the focus-modulation frequency higher than the frequency of the highest intensity-modulation component. However, if the desired focus-modulation frequency be very high, it may be necessary to tune focusing coil 16.

In Figure 2, voltage V_1 represents the signal capacitively picked up by element 20. As previously indicated, the voltage V_1 is substantially 180° out of phase with the sine wave variations in focusing current, as depicted by current wave I_1 in Figure 2.

The output voltage V_a of tuned amplifier 26 is applied across load resistor 27 of the phase-comparator, and instantaneous voltages V_a of equal magnitude and like polarity appear at the opposing ends of secondary winding S of transformer 11. These voltages, however, represent but one component of the total voltage appearing at each end of secondary winding S. The other component comprises a voltage W_s induced in secondary S from primary winding P. As described earlier, the primary winding P of transformer 11 is in parallel with series-combined resistors 12-13 so far as the output of sine wave oscillator 10 is concerned. Consequently, a voltage W_s corresponding to that of sine wave voltage W, but substantially 180° out of phase therewith, is induced in secondary winding S; and at any given instant, the induced potentials of voltage W_s at opposite ends of secondary S are of equal magnitude and opposite polarity.

It will be seen then that the instantaneous magnitudes of the two voltages V_a and W_s are additive at one end of secondary S and subtractive at the opposite end. The constants of the system may be so selected that the peak-to-peak voltage W_s induced in secondary S from primary winding P is of the same general order of magnitude as

the maximum peak-to-peak voltage V_a derived from amplifier 26. When this condition obtains, the component voltages at the subtractive end of secondary S tend to cancel completely each other and the resultant voltage is hence substantially zero, while at the additive end of secondary S the resultant voltage is substantially twice that of either component.

If, in the circuit of Figure 1, the output voltage V_a of amplifier 26 is out of phase with the voltage W applied across primary winding P, then the voltages will be additive at the lower end of secondary S, and subtractive at the upper end. Assuming this to be the situation, and assuming, for purposes of illustration, the peak-to-peak amplitude of voltage W_s to be slightly greater than that of voltage V_a , a relatively large positive D.-C. voltage, corresponding to the sum of the peak amplitudes of voltages V_a and W_s , will be developed across R. C. network 34 by the peak-detector action of diode 29 operating in cooperation with network 34; and a relatively small negative D.-C. voltage, corresponding to the difference between the peak amplitudes of voltages V_a and W_s , will be developed across R. C. network 30 by the peak-detector action of diode 28 operating in cooperation with network 30.

The resistor and capacitor elements comprising R. C. networks 30 and 34 are sufficiently large to provide the desired long time constant. When the focus-control circuit is employed in a television receiver, the time constant of networks 30 and 34 may preferably be of the order of the duration of at least several frames.

The positive D.-C. voltages developed across network 34, and the negative D.-C. voltages developed across network 30, are combined and the resultants are utilized as focusing-control, i. e. focusing-correcting, voltages. In Figure 1, the said voltages are differentially combined in voltage-combining network 38 and the resultant voltage is applied to the control grid of tube 14. In the specific situation assumed above, the negative D.-C. voltage developed across network 30 is substantially smaller in magnitude than the positive D.-C. voltage developed across network 34, and the arithmetical mean of the combined voltages is a positive voltage which is applied to the control grid of tube 14. Resistors 39 and 40 of combining network 38 are substantially larger in value than resistors 32 and 36 of R. C. networks 30 and 34, in order not to disturb the operation of the phase comparator.

As previously indicated, tube 14 is operated as a low-gain class A amplifier, and the effect of the application of the positive D.-C. correcting voltage to the control grid of tube 14 is merely to increase the D.-C. component of the current flowing through auxiliary focusing coil 16; the A.-C. component is not affected to any substantial degree. The result of such an increase in total focusing current is to move the mean focus of beam 25 in the direction of sharp or optimum focus.

And it will be evident to those skilled in the art that, by suitable selection of circuit parameters, the correcting or control voltage obtained from voltage-combining network 38 may be of such magnitude and polarity as to move the focus of beam 25 substantially all the way to optimum focus.

Consider now the situation where the beam is over-focused. In Figure 2, voltage V_2 represents the signal derived by element 20 when

the total average focusing current is seven units and the beam is over-focused. And, as is expected from the shape of the pickup-voltage versus focusing-current curve, voltage V_2 is of opposite phase to, and of smaller amplitude than, voltage V_1 .

When voltage V_2 in amplified form is applied across resistor 27, the phase relationship between the two voltage components V_a and V_b in secondary winding S is reversed, i. e. the voltage components at the upper end of secondary S are in phase and hence additive, while the voltage components at the lower end of secondary S are substantially 180° out of phase and hence subtractive. In this situation, a relatively large negative D.-C. voltage is developed across R. C. network 30, corresponding to the sum of the peak amplitudes of voltages V_a and V_b , by the peak-detector action of diode 28 and network 30 and a small positive D.-C. voltage, corresponding to the difference between the peak amplitudes, tends to be developed across network 34. The negative and positive D.-C. voltages are combined in voltage-combining network 38, and the mean voltage, negative in polarity, being impressed upon the control grid of tube 14, has the effect of decreasing the D.-C. component of current flowing through auxiliary focusing coil 16. The focus of beam 25 is thereby moved from an over-focused condition to optimum condition.

Consider now the situation where beam 25 is sharply focused. In the illustration shown in Figure 2, a condition of sharp focus occurs when the total average focusing current is five units, and the voltage then picked up by element 20 is depicted by voltage V_3 . Observe that the frequency of voltage V_3 is twice that of the A.-C. focusing-current component I_3 derived from the voltage W delivered by sine wave oscillator 10 and applied to auxiliary focusing coil 16 by way of tube 14. Since amplifier 26 is tuned to the frequency of oscillator 10, the voltage V_3 , picked up by element 20 when beam 25 is at optimum focus, does not pass through amplifier 26 and does not appear in the output circuit thereof. Hence when beam 25 is at sharp focus, the voltage across secondary S comprises only that voltage induced therein from voltage W . The instantaneous voltages at opposite ends of secondary S are then equal in magnitude and opposite in polarity. Equal and opposite D.-C. voltages are then developed across networks 30 and 34 which, when combined in voltage-combining network 38, substantially cancel each other. In short, when beam 25 is at optimum focus, the correcting voltage applied to the control grid of tube 14 is of zero magnitude.

Thus far it has been assumed that electron beam 25 is not intensity modulated. However, if the focus control system is to be utilized in television systems, as is contemplated, the electron beam will ordinarily be intensity modulated during a major portion of the scanning operation; and in radar applications, also, the beam intensity varies with the strength of the reflected signals. It is accordingly important that the focus control system of the present invention operate satisfactorily whether or not the beam is intensity modulated. The effect of intensity modulating the beam upon the operation of the focus control system will now be considered.

Attention is first invited to the fact that amplifier 26 is tuned to the frequency of oscillator 10. Consequently, if the frequency of oscillator 10 be higher than that of the highest intensity-

modulating signal, for example, higher than the highest video frequency, then amplifier 26 will effectively suppress all of the intensity-modulating frequencies. If the frequency of oscillator 10 be lower than the highest intensity-modulating frequency, substantially all intensity-modulating frequencies, except those in the vicinity of the oscillating frequency, will be effectively suppressed, and consequently, the disturbing effect upon the focus control system will, in most cases, be negligible.

In those instances where the effect of intensity modulating the beam is expected to be objectionable, it will ordinarily be possible to demodulate the beam for a short period, during which time the focus control system may operate to develop the necessary control voltages.

Illustrated in Figure 1 are means readily employable in conventional television systems for providing a beam of substantially fixed intensity during the first few horizontal deflections at the top of the frame, where the phosphor may either be omitted or masked.

In Figure 1, block 41 represents the R.-F. amplifier, video I.-F. amplifier and video detector circuits of a conventional television receiver. Block 42 represents the video amplifier, block 43 the synchronizing-separator circuit, and block 44 the vertical-synchronizing amplifier circuit, all well known in the television arts.

In a conventional television receiver, the screen is ordinarily blanked out between fields for a period equal to about sixteen horizontal lines. The sixteen lines of the vertical-blanking interval are subdivided as follows: the first three lines are occupied by the equalizing pulses; and the next three lines are occupied by the vertical-synchronizing pulse, following which the screen remains blanked for a period equal to approximately ten lines. The beam makes its vertical return sweep, i. e., the beam moves from the bottom of the frame to the top, in the three horizontal-line periods immediately following the termination of the vertical-synchronizing pulse. It will be seen then that the screen remains blanked for about seven horizontal lines following the arrival of the beam at the top of the screen. Hence, if desired, the screen may be unblanked during at least a portion of the time occupied by these seven lines, i. e., the screen may be unblanked during the period that the beam is at the top of the screen prior to the arrival of the first video-intelligence signal for the particular field.

Referring now to Figure 1, a portion of the energy of the vertical-synchronizing pulse is applied to time-delay circuit 45 wherein a delay is introduced equal to about three horizontal lines. The pulse delivered by time-delay circuit 45 is employed to trigger multivibrator circuit 46 which is arranged to deliver a positive pulse having a duration equivalent to about six horizontal lines. The positive pulse from multivibrator 46 is combined with the output of video amplifier 42 in voltage-combining circuit 41 and the output thereof is applied to grid 23 of cathode-ray tube 17. Time-delay circuits, multivibrator circuits, and voltage-combining circuits, of the types required are all well known in the television and/or radar arts and it is not believed necessary, therefore, either to illustrate or to describe these circuits.

By the means briefly described above, screen 24 of cathode ray tube 17 is unblanked, and beam 25 is of substantially fixed intensity, for a period

of about six lines at the top of each field. As previously indicated, the phosphor may be omitted from the area corresponding to these six lines, or alternatively, the screen may be masked in this area.

It will be understood that modifications may be made in the circuit of Figure 1 without departing from the basic concept of the invention. For example, it is not essential that a second focusing coil be employed. If desired the focus-modulating voltage may be applied across the main focus coil. Nor is it essential that the modulating voltage be in sine wave form. If desired voltage pulses of preselected polarity may be used. And of course the phase comparison between the modulating and pickup voltages may be accomplished by other known means.

It is seen that I have provided means for quickly and automatically achieving sharp focus irrespective of the setting of the manual focusing control. And once achieved sharp focus is thereafter maintained since any tendency of the focus to depart toward either an underfocused or over-focused condition is substantially instantly met by a force tending to prevent the departure.

Having described my invention, I claim:

1. In a cathode-ray system; a cathode-ray tube having a screen, means for generating an electron beam, and focus-control means for said beam; and means responsive to changes in screen potential resulting substantially from changes in beam focus for developing voltages whose magnitude and phase are a function of the extent and direction respectively of the departure of the mean focus of said beam from sharp focus.

2. In a cathode-ray system; a cathode-ray tube having a screen, means for generating an electron beam, and means for controlling the focus of said beam; and means responsive to changes in screen potential resulting substantially from changes in beam focus for developing control voltages whose polarity and magnitude indicate respectively the direction and extent of the departure of the mean focus of said beam from sharp focus.

3. In a cathode-ray system; a cathode-ray tube having a screen, means for generating an electron beam, and means for controlling the focus of said beam; means responsive to changes in screen potential resulting substantially from changes in beam focus for developing control voltages whose polarity and magnitude indicate respectively the direction and extent of the departure of the mean focus of said beam from sharp focus; and means for applying said control voltages to said focus-control means to oppose said departure.

4. In a cathode-ray system; a cathode-ray tube having a screen, means for generating an electron beam, and focus-control means for said beam; means, including a conductive element coupled to said screen, for deriving unidirectional voltages whose magnitude and polarity are a function of the mean focus of said beam; and means responsive to said unidirectional voltages for modifying the mean focus of said beam in accordance with the magnitude and polarity of said derived voltages.

5. In a cathode-ray system; a cathode-ray tube having a screen, means for generating an electron beam, and means for controlling the focus of said beam; means for causing said beam to deviate periodically from mean focus at a pre-selected frequency and by a predetermined amount; and means responsive to said periodic deviations for deriving voltages whose phase and magnitude indicate respectively the direction and

extent of the departure of said mean focus from sharp focus.

6. In a cathode-ray system; a cathode-ray tube having a screen, means for generating an electron beam, and means for controlling the focus of said beam; means for causing said beam to deviate periodically from mean focus at a pre-selected frequency and by a predetermined amount; means responsive to said periodic deviations for deriving unidirectional voltages whose polarity and magnitude indicate respectively the direction and extent of the departure of said mean focus from sharp focus; and means for applying said unidirectional voltages to said focus control means to reduce said departure to substantially zero.

7. In the combination claimed in claim 6 characterized in that said periodic deviations of said beam from mean focus are so small as to be substantially imperceptible to the unaided human eye.

8. In a cathode-ray system; a cathode-ray tube having means for generating an electron beam, means for focusing said beam, and a screen; means for applying a direct-current voltage to said focusing means to control the mean focus of said beam; means for applying a periodic voltage to said focusing means to alter periodically the focus of said beam at a predetermined frequency and by a predetermined amount; and means, including a conductive element mounted in proximity to at least a portion of said screen, for deriving voltages corresponding to voltage variations in said screen resulting substantially from said periodic alterations in the focus of said beam, the magnitude and phase of said derived voltages being a function of the extent and direction of the departure of the mean focus of said beam from sharp focus.

9. In a cathode-ray system; a cathode-ray tube having means for generating an electron beam, means for focusing said beam, and a screen; means for applying a direct-current voltage to said focusing means to control the mean focus of said beam; means for applying a periodic voltage to said focusing means to alter periodically the focus of said beam at a predetermined frequency and by a predetermined amount; means, including a conductive element mounted in proximity to at least a portion of said screen, for deriving voltages corresponding to voltage variations in said screen resulting substantially from said periodic alterations in the focus of said beam, the magnitude and phase of said derived voltages being a function of the extent and direction of the departure of the mean focus of said beam from sharp focus; means for detecting the magnitude and phase of said derived voltages; and means for applying said detected voltages to said focusing means to alter said mean focus in such direction and to such an extent as to reduce the magnitude of said derived voltages to a minimum value.

10. In a cathode-ray system; a cathode-ray tube having a screen, means for generating an electron beam, and focus-control means for said beam; a source of periodic voltage; means for applying said periodic voltage to said focus-control means to modulate the focus of said beam; a phase-comparing circuit; means for applying said periodic voltage to said phase-comparing circuit; a conductive element mounted in cooperative relation with said screen for capacitively coupling said screen to said phase-comparing circuit; and means, including said phase-compar-

11

ing circuit, for developing control voltages indicative of the magnitude and direction of the departure of the mean focus of said beam from sharp focus.

11. The combination claimed in claim 10 characterized in that means are provided for applying said control voltages to said focus-control means to alter the mean focus of said beam in such manner that said mean focus tends to correspond to sharp focus.

12. In a cathode-ray system; a cathode-ray tube having a screen, means for generating an electron beam, and focus-control means for said beam; a source of voltage having D.-C. and A.-C. components; means for applying said voltage to said focus-control means in such manner that said D.-C. component controls the mean focus of said beam and said A.-C. component controls the frequency and extent of the excursions of said beam from said mean focus; and means, coupled to said screen, responsive to changes in screen potential resulting substantially from said excursions of said beam from mean focus for developing voltages whose phase and magnitude indicate respectively the direction and extent of the departure of the mean focus of said beam from sharp focus.

13. In a cathode-ray system; a cathode-ray tube having a screen, means for generating an electron beam, and means for controlling the focus of said beam; a source of voltage having

12

D.-C. and A.-C. components; means for applying said voltage to said focus-control means in such manner that said D.-C. component controls the mean focus of said beam and said A.-C. component controls the frequency and extent of the excursions of said beam from mean focus; means, coupled to said screen, responsive to changes in screen potential resulting substantially from said excursions of said beam from mean focus for developing control voltages whose polarity and magnitude indicate respectively the direction and extent of the departure of the mean focus of said beam from sharp focus; and means for applying said control voltages to said focus-control means to oppose said departure.
